COMBINATION LOCK

Jerome L. Formo, Howard Arved Johnson, and
Richard E. Jacobson, Minneapolis, Minn.

Application November 22, 1947, Serial No. 787,602

4 Claims. (Cl. 70—285)

1

This invention relates to a lock responsive for opening to the insertion of a key or to the dialing of the proper predetermined combination.

It is an object of our invention to provide a novel and highly efficient key opening combination lock, particularly adapted for use in cylinder tumbler locks.

More specifically, it is an object to provide a lock having a longitudinally displaceable cylinder with locking tumblers mounted therein and adapted to be displaceable only when the proper combination has been dialed whereby said lock may be opened, said tumblers being responsive to the insertion of a key to release said cylinder and permit the lock to be opened.

These and other objects and advantages of our invention will more fully appear from the following description made in connection with the accompanying drawings wherein like reference characters refer to similar parts throughout the several views and in which:

Fig. 1 is an enlarged longitudinal vertical sectional view showing one side of the lock and casing therefor;

Fig. 2 is a transverse vertical sectional view taken substantially along the line 2—2 of Fig. 1;

Fig. 3 is a transverse vertical sectional view taken substantially along the line 3—3 of Fig. 1;

Fig. 4 is a front elevational view of the lock showing the dial;

Fig. 5 is a perspective view of a typical combination disc; and,

Figs. 6 and 7 are longitudinal vertical sectional views of the two casing sections.

As shown in the accompanying drawings particularly Figs. 6 and 7, we provide a lock casing 10 longitudinally split into two sections 10a and 10b. Each section being recessed to form a cylinder receiving chamber 11 therein when said sections are in assembled position. One of the sections 10a has a plurality of spaced, grooved tumbler trackways 12 transversely formed in an intermediate portion thereof leaving tumbler obstructing flanges 13 therebetween. The extremities of said obstruction flanges 13 are cut back to respectively form one half of a pair of longitudinally disposed tumbler receiving slots 14. The other half of said slots 14 is formed by cutting back corresponding portions of the casing section 10b. These opposed tumbler receiving recesses are best shown in Fig. 3. A plurality of transversely disposed longitudinally spaced disc receiving grooves such as the three grooves 15 are formed in the inner peripheral surface of the chamber 11 in the outer

2

portions of casing sections 10a and 10b, the grooves in one section being adapted to be aligned with the grooves in the other section when said two sections are in assembled position. An elongated tumbler carrying cylinder 16 is adapted to be rotatably mounted in said chamber 11 in longitudinally displaceable relation therein. As best shown in Fig. 3, a plurality of transversely disposed tumblers 17 are slidably mounted in longitudinally spaced relation through an intermediate portion of said cylinder 16. Each tumbler 17 has an individual spring 18 to resiliently urge said tumbler outwardly into projected position. The tumblers 17 have longitudinally aligned key receiving slits 19 and the cylinder 16 has a longitudinally disposed key receiving passage 16a therethrough and said tumbler slits 19 are substantially aligned and have their side extremities substantially aligned with said passage 16a. The lower ends of the tumbler slits 19 are urged upwardly from the lower portion of passage 16a by the spring 18 and the slits 19 in their respective tumblers 17 are of various lengths so that only a key having a certain predetermined contour will retract said tumblers 17 from the slot 14 when inserted into the key receiving passage 16a and through the respective slits 19. We refer to upper and lower portions of the tumblers as shown in Figs. 1 and 3 merely for convenience and it is understood that these references to upper and lower might well be interchanged depending upon the position of the lock. The tumblers 17 and portion of the cylinder 16 adjacent thereto are of substantially conventional design and cooperate with the combination portion of the lock as will hereinafter be described.

The combination portion of the lock consists in a plurality of combination discs such as the three discs 20 which are journaled on the outer portion of the cylinder 16 and are adapted to be rotatably received in the respective disc receiving grooves 15. As best shown in Fig. 2, the cylinder 16 has a plurality of disc stops such as the three stops 21. In Fig. 1 these stops 21 are all shown in aligned longitudinally spaced relation and they would operate perfectly in this position. However, in order to make it more difficult to operate, the combination with a plurality of different stopping points for the several discs, these stops 21 are peripherally spaced about the circumference of the cylinder 16 as well as being longitudinally spaced thereon. A disc rotating and control sleeve 22 is journaled on the outer portion of cylinder 16 and has its inner extremity fixed to the outermost disc 20. An inner

peripheral recess 23 is formed around the inside periphery of sleeve 22 and is adapted to receive the outermost stop 21 therein. This peripheral recess 23 is disposed adjacent the outermost disc 20 as best shown in Fig. 1 and its width is substantially equal to the spacing between the discs 20. Each of the discs 20 has a stop receiving notch 24 formed in the inner peripheral edge thereof and the notches 24 of the respective discs 20 are adapted to receive the respective stops. The center disc 20 has a longitudinally disposed detent 25 fixed to each face thereof. The innermost disc 20 has an outwardly disposed detent 25 which is adapted to be engaged by the inwardly facing detent 25 of the center disc 20. The outermost disc 20 has an inwardly disposed detent 25 which is adapted to engage the outwardly extending detent 25 of the center disc 20. A latch actuating bar 26 is mounted at the inner extremity of casing 10 and an inwardly extending annular flange 27 retains the outer end of said bar 26 in rotatably mounted position at the inner end of said casing 10. A recess is provided in the outer portion of bar 26 and a resilient spring 28 is placed in this recess and interposed between said bar 26 and the inner end of cylinder 16 to resiliently hold said cylinder in outwardly disposed position. A second recess 29 is formed in the outer portion of bar 26 in laterally off-set position from the longitudinal center line thereof and a projection 30 on the inner end of cylinder 16 is adapted to be slidably received in said recess 29 to rotate said bar 26 when said cylinder 16 is rotated in casing 10.

Means are provided for maintaining said casing sections 10a and 10b in proper predetermined opposed position such as the four pins 31 in section 10b adapted to be respectively received in four apertures 32 in section 10a when the two sections are in assembled position. A retaining sleeve 33 is pressed over the two sections 10a and 10b to securely hold the same in assembled position with the bar 26 retained at the inner portion thereof.

Operation

The following is a description of the operation of our lock. The lock is mounted in position substantially as shown in Fig. 1 and an outer annular flange 34 is provided to butt against a flat surface such as the door of an automobile. In normal position, the tumblers 17 are resiliently projected upwardly into the slots 14 and are in alignment with the respective tumbler stop flanges 13 to prevent rotation of said cylinder. The notches 24 of the discs 20 are not aligned with their respective stops 21 and thus the discs 20 prevent the cylinder 16 from being inwardly displaced.

By inserting a key having the proper contour in the key receiving passage 16a, the tumblers 17 are retracted against the resilient force of their respective springs 18 and the cylinder 16 turned in the normal manner to turn bar 26 and open the lock.

However, if the key is lost, our lock may be opened by rotating the discs 20 so that their respective notches 24 are respectively aligned with the stops 21 to permit said cylinder 16 to be displaced inwardly against the resilient force of spring 28 and thereby align said tumblers 17 with their respective grooved trackways 12. A numbered dial 35 is mounted on the outer surface of sleeve 22 in the conventional manner and as the sleeve 22 is rotated the disc detents 25 turn the respective discs and by turning the proper pre-

determined combination of numbers, the notches 24 are respectively aligned with their respective stops 21.

It will be seen that we have provided an extremely simple, highly efficient combined combination and key opening tumbler lock. It should be noted that adequate means are provided on the outer extremity of cylinder 16 such as the knurled portion 36 which will provide an adequate frictional surface by which the cylinder 16 and bar 26 may be turned after said cylinder 16 is displaced inwardly. Our lock is extremely convenient in the event that several people are using a car and a limited number of keys are available therefor, as well as in the case of a car owner losing his keys. This lock is adapted for a wide variety of uses such as house doors as well as automobile doors and the like.

It will, of course, be understood that various changes may be made in the form, details, arrangement and proportions of the parts without departing from the scope of our invention.

What we claim is:

1. A lock adapted to be opened by either key or combination, said lock comprising a lock casing having a cylinder receiving chamber formed therein and having a plurality of transverse grooved tumbler trackways spaced longitudinally of the casing chamber and formed around the inner periphery thereof, a plurality of rotation arresting elements longitudinally separating said trackways, there being circumferentially spaced longitudinally disposed tumbler receiving slots formed within said chamber and extending across said rotation arresting elements, and said casing also having a plurality of disc receiving grooves spaced longitudinally of said casing and formed around the inner periphery thereof in longitudinally spaced relation from said tumbler trackways, a tumbler carrying cylinder rotatably inserted into said chamber in longitudinally displaceable relation thereto and having a longitudinally disposed key receiving passage therein, a plurality of normally projected tumblers respectively mounted in an intermediate portion of said cylinder, a plurality of combination discs journaled on said cylinder and respectively received by said disc receiving grooves, means for normally urging said cylinder outwardly, means at the outer portion of said cylinder for selectively turning said discs, stop means for normally preventing said cylinder from sliding longitudinally relative said discs, and means for bypassing said stop means when said discs are turned to a selected predetermined position, whereby said cylinder may be pressed inwardly to respectively align said tumblers with said trackways and permit said cylinder to be rotated in said casing to open said lock.
2. A lock adapted to be opened by either key or combination, said lock comprising a lock casing having a cylinder receiving chamber formed therein and having a plurality of transverse grooved tumbler trackways spaced longitudinally of the casing and formed around the inner periphery thereof, a plurality of tumbler obstructing flanges separating said trackways, there being circumferentially spaced longitudinally disposed tumbler receiving slots formed within said chamber and extending across said flanges, said casing also having a plurality of disc receiving grooves spaced longitudinally of said casing and formed around the inner periphery thereof in longitudinally spaced relation from said tumbler trackways, a tumbler carrying cylinder rotatably

inserted into said chamber in longitudinally displaceable relation thereto and having a longitudinally disposed key receiving passage therein, a plurality of resiliently projected tumblers retractably mounted in an intermediate portion of 5 said cylinder, each of said tumblers having a key receiving slit formed therein, the side portions of said slits being longitudinally aligned with said key receiving passage, said tumblers being responsive for retraction to the insertion through 10 said aligned slits of a key having the proper contour, a plurality of combination discs journaled on said cylinder and respectively received by said disc receiving grooves, means at the outer portion of said cylinder for selectively turning said discs, 15 means for normally urging said cylinder outwardly, a plurality of longitudinally spaced stops fixed in outstanding relation to the surface of said cylinder and disposed respectively outwardly from said discs to normally respectively engage 20 thereagainst, said discs having elements formed therein for receiving said stops to by-pass said stops when aligned therewith to permit said cylinder to be pressed inwardly to respectively align said tumblers with said trackways whereby said 25 cylinder may be rotated to open said lock.

3. A lock adapted to be opened by either key or combination, said lock comprising a longitudinally split lock casing having a cylinder receiving chamber formed therein and having a plurality of transverse grooved tumbler trackways spaced longitudinally of the casing and formed around the inner periphery thereof, a plurality of tumbler obstructing flanges interposed between said trackways, there being circumferentially spaced longitudinally disposed tumbler receiving slots formed within said chamber and extending longitudinally through said flanges, said casing also having a plurality of disc receiving grooves spaced longitudinally thereof and formed around the inner periphery thereof in outwardly spaced relation from said tumbler trackways, a tumbler carrying cylinder rotatably mounted between the sections of said split casing in longitudinally displaceable relation thereto and having a longitudinally disposed key receiving passage therein, a plurality of longitudinally spaced resiliently projected tumblers retractably mounted in an intermediate portion of said cylinder, each of said tumblers having a key receiving slit formed therethrough, the side portions of said slits being longitudinally aligned with said key receiving passage, said tumblers being responsive for retraction to the insertion through said aligned slits of a key having the proper contour, a plurality of combination annular discs journaled on said cylinder and respectively received by said disc receiving grooves, means at the outer portion of said cylinder for selectively turning said discs, indicia means for indicating the position of said discs, means for normally urging said cylinder outwardly, and a plurality of longitudinally spaced stops fixed in outstanding relation to the surface of said cylinder and disposed respectively adjacent the outward surface of said discs to normally engage thereagainst, each of

said annular discs having a stop receiving notch formed in the inner periphery thereof for respectively by-passing said stops when aligned therewith to permit said cylinder to be pressed inwardly to respectively align said tumblers with said trackways whereby said cylinder may be rotated to open said lock.

4. A lock adapted to be opened by either key or combination, said lock comprising a lock casing having a split cylinder receiving chamber formed therein and having a plurality of transverse grooved tumbler trackways spaced longitudinally of the casing and formed around the inner periphery thereof, tumbler obstructing flanges separating said trackways, there being circumferentially spaced longitudinally disposed tumbler receiving slots formed within said chamber and extending across said flanges, said casing also having a plurality of disc receiving grooves spaced longitudinally of said casing and formed around the inner periphery thereof in longitudinally spaced relation from said tumbler trackways, a tumbler carrying cylinder rotatably inserted into said chamber in longitudinally displaceable relation thereto and having a longitudinally disposed key receiving passage therein, a plurality of resiliently projected tumblers retractably mounted in an intermediate portion of said cylinder, means associated with said tumblers and adapted to cooperate with a key having the proper contour to retract said tumblers when said key is inserted in said key receiving passage, a rotatable bolt actuating element journaled in the rear of said casing and normally closing the same in normally inwardly spaced relation from the inner end of said cylinder, a resilient spring interposed between said bolt actuating element to normally urge said cylinder into outward position, a connection between said cylinder and said bolt actuating element for turning said element when said cylinder is turned, a plurality of annular combination discs journaled for rotation on said cylinder and respectively received by said disc receiving grooves, 35 stop means mounted on said cylinder for normally preventing the inward displacement thereof, means at the outer portion of said cylinder for selectively turning said discs, and means on said discs for respectively by-passing said stop means to permit said cylinder to be pressed inwardly and respectively align said tumblers with said trackways whereby said cylinder and said bolt actuating element may be rotated to open said lock.
